UNITED STATES PATENT OFFICE.

BENGT M. W. HANSON, OF HARTFORD, CONNECTICUT. ASSIGNOR TO PRATT & WHITNEY COMPANY, OF HARTFORD, CONNECTICUT, A CORPORATION OF NEW JERSEY.

STEADY-REST.

1,182,478.

Specification of Letters Patent.

Patented May 9, 1916.

Application filed October 21, 1915. Serial No. 57,101.

To all whom it may concern:

Be it known that I, BENGT M. W. HANSON, a citizen of the United States, residing at Hartford, in the county of Hartford and 5 State of Connecticut, have invented certain new and useful Improvements in Steady-Rests, of which the following is a specification.

This invention relates to steady-rests, the 10 object being to provide an effective, readily-operable device of this character, which will substantially and solidly resist the thrust of an article such as the work with which the said steady-rest is associated.

15 A steady-rest embodying my invention is susceptible of general use, although it is of particular advantage when employed as a part of or in conjunction with a metal-reducing machine, an illustration of which is 20 found in my contemporaneously pending application filed October 21, 1915, Serial No. 57,102.

In the drawings accompanying and forming part of the present specification I have 25 shown in detail one convenient form of embodiment of the invention which to enable those skilled in the art to practise the same will be set forth fully in the following description. I do not limit myself to this particular disclosure; I may depart therefrom in several respects within the scope of the invention defined by the claims following said description.

Referring to said drawings: Figure 1 35 shows a work-carrier and in dotted outline part of the wheel of a grinding-machine, the carrier represented in side elevation, being equipped with a steady-rest involving the invention. Fig. 2 is a front view of said 40 steady-rest. Fig. 3 is a detail view in top plan, of the movable elements of the steady-rest and stops associated therewith. Fig. 4 is a view of the parts shown in Fig. 3 as seen from the left, the dotted lines illustrating 45 work.

Like characters refer to like parts throughout the several views.

In Fig. 1 I have represented the movable carrier 2 and the grinding-wheel 3 of a 50 grinding machine such as disclosed in my said other application, this carrier 2 presenting a suitable support for my steady-rest, al-

though as will be clear, this steady-rest is capable of successful use in other connections. The steady-rest comprises two elements, the operative portions of which are adapted to engage the work at circumferentially separated points. These elements preferably but not essentially are of swinging type, and although it is conceivable that 55 they might move about the same axis, they preferably turn about independent axes which are best disposed in parallelism. The elements in question are movable in one direction manually and in the other mechanically as by spring means. In the present case the elements are movable into work engaging relation by hand and out of working relation by spring means of suitable kind. The different parts of the steady-rest 60 may be mounted in any desirable manner, the support or body portion 4, practically in the form of a block, answering satisfactorily in this connection. This body portion or block 4 virtually straddles the movable 65 work-carrier 2 and is connected thereto in some convenient rigid manner, for instance by one or more screws as 5. Within the body portion 4 are mounted the shafts 6 and 7, said shafts being in parallelism and the 70 body portion being provided with suitable bearings to support said shafts for rocking motion. To the shafts 6 and 7 are rigidly connected in some suitable manner the forwardly extending arms 8 and 9 which as illustrated, cross each other. In addition to the 75 arms 8 and 9 the shafts have rigidly fastened thereto the outwardly-extending arms 10 and 11, each shaft with its two arms in the organization shown, constituting one of the elements 80 of the steady-rest to which I have already briefly alluded. The arms 8 and 9 are furnished at their front ends with the hardened members 12 and 13 connected thereto in any suitable manner as by screws, these members 85 12 and 13 presenting the operative or working portions of the movable elements of the rest. Their free or front ends are flattened and are adapted to engage the work at circumferentially separated places. The flattened faces of the work engaging elements 12 and 13 are on angles which converge outward, thus providing a ready means for receiving the work 14 as shown by dotted lines

in Fig. 4, within the members or jaws 12 and 13. The work may be positioned on the carrier 2 in any suitable manner; for instance it may be located between centers (not shown) 5 and rotated in any desirable way. These hardened members or jaws 12 and 13 are closed upon the work preferably by the operator, the arms 10 and 11 being provided with handles 15 to facilitate their operation.

10 As already observed I prefer to close the complementary steady-rest elements upon the work by hand and to open them mechanically. To open said elements a spring as 16 may be utilized, this spring being of expanding type and its terminals being seated in mating sockets as 17 on the inner sides of the arms 10 and 11 near their axes of oscillation, the spring exerting a constant tendency to separate or expand the arms 10 and 20 11 and as a consequence owing to the fact that the arms 8 and 9 are crossed, to constantly expand said arms 8 and 9 and thereby open the jaws 12 and 13.

The action is as follows: Normally the 25 jaws 12 and 13 will be spread, this relation being maintained by the spring 16. At this time the projection 18 on the arm 8 acting as a stop abuts against the hub of the arm 9, thus preventing abnormal opening movement of the jaws 12 and 13. The work having been mounted and having with the wheel 3 been set in action to effect its rotation, the handles 15 will be simultaneously grasped and closed toward each other, 30 thus closing the jaws 12 and 13 upon the work, the operator regulating the grip of the jaws on the work and increasing the pressure as the work is reduced. In view of this condition the jaws 12 and 13 can engage the work where it is being reduced and 40 practically opposite each other.

I provide means of a positive nature for arresting the motion of the jaws 12 and 13 when the work has been reduced the requisite extent or when some similar function 45 has been performed. This means may vary decidedly, although adjustable means as the screws 19 and 20, are preferred, the screw 19 being coöperative with the stop arm 21 50 fastened to the shaft 6, while the screw 20 is coöperative with the stop arm 22 fastened to the shaft 7. The screws present as will be evident merely one form of adjustable stops. Others might be substituted therefor. The screws are tapped into the body 55 portion 4 from the outside thereof and their inner ends or tips are in the path of movement of the respective stop arms 21 and 22. It will be clear that when the stop arms engage the respective screws, further movement of the arms 10 and 11 by the operator will be effectually prevented. By the adjustment of these screws 19 and 20, the amount of movement of the arms, and as a 60 result the extent of closing movement of the

jaws 12 and 13 can be regulated. In view of this condition I can prevent the motion of the jaws 12 and 13 when the work has been reduced to the requisite extent. The body portion 4 is chambered or hollowed to 70 provide for the necessary motion of the several arms and to position the screws 19 and 20, so that they can coact with the stop arms 21 and 22 respectively.

I may if desired provide the diamond or 75 equivalent as 23 to dress the wheel 3, the carrier 24 for said diamond being provided with the customary adjuncts, among which is the hand wheel 25, as is common in grinding machines. The carrier of shank 24 is 80 adjustable and is held in its adjusted position by the screw 24'. Water or something of a similar nature, may be supplied to the grinding zone in any convenient way, as by the pipe 26.

It will be clear from the foregoing description that I provide means such as jaws for engaging work and for applying to the two means or jaws uniform or balanced pressures, the pressures in the present case 90 being toward the work. This result is obtained in the showing made by separately movable manually operable elements which respectively carry the separate means or 95 jaws.

I may if desired, provide for the rock 95 shafts 6 and 7 the oilers 30 (Fig. 2).

What I claim is:

1. A steady rest comprising two movable members each having a jaw to engage the 100 work and each member having a handle portion, the handle portions being so related with each other that they can be simultaneously grasped by the hand and the jaws being rigid with the respective handle portions whereby when the handle portions are moved toward each other the jaws will be 105 directly closed.

2. A steady rest comprising two movable members each having a jaw to engage the 110 work and each member having a handle portion, the handle portions being so related with each other that they can be simultaneously grasped by the hand to effect the approach of the jaws toward each other, and means settable at will, for arresting the approaching movement of the jaws at a pre-determined point.

3. A steady rest comprising separate 115 means each movable, for engaging the work at circumferentially separated places, manually operable means for simultaneously closing said means upon the work, and means tending constantly to separate said work-engaging means.

4. A steady rest comprising two swinging 120 members having crossed portions at one side of their axes of motion, and handle portions at the other side of said axes, the crossed portions being provided with jaws disposed 125

opposite each other and the handle portions when grasped being adapted to cause the movement of the jaws toward each other.

5. A steady-rest comprising two movably mounted members each provided with a work-engaging jaw and spring means tending constantly to separate said jaws.

6. A steady rest comprising two crossed swinging members provided with work engaging jaws, manually operable means for closing said jaws, and spring means tending to constantly open said jaws.

7. A steady rest comprising two crossed swinging members provided with work in closing jaws, manually operable means for closing the jaws, spring means tending constantly to open the jaws, and adjustable means for limiting the amount of closing movement of the jaws.

20 8. A steady rest comprising two movably mounted members each provided with a work-engaging jaw, fixed means for limiting the opening movement of the jaws, adjustable means for limiting the closing move-

ment of the jaws, manually operable means 25 for closing the jaws, and spring means tending constantly to open the jaws.

9. A steady rest comprising two rock shafts, arms rigid with the respective shafts and extending forwardly therefrom, the arms 30 crossing forward of the shafts and being provided with jaws to jointly receive the work, arms rigid with the respective shafts and extending rearwardly therefrom, the last mentioned arms being provided with handles to be simultaneously grasped by the same hand, the spring means tending constantly to act to separate said last mentioned arms, stop arms fastened to the respective shafts, and screws to limit the motion of 40 said stop arms.

In testimony whereof I affix my signature in presence of two witnesses.
